UNITED STATES PATENT OFFICE

FRANKLIN P. BAKER, OF BOSTON, MASSACHUSETTS.

PICTURE-HOOK.

SPECIFICATION forming part of Letters Patent No. 257,457, dated May 9, 1882.

Application filed September 9, 1881. (No model.)

To all whom it may concern:

Be it known that I, FRANKLIN P. BAKER, a citizen of the United States, residing at Boston, in the county of Suffolk and State of Massachusetts, have invented certain new and useful Improvements in Picture-Hooks; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to picture-hooks formed or struck up from a flat band of sheet metal or from bent wire, the object of such invention being to prevent the accidental disengagement of the hook from the molding, which now frequently occurs when attempts are made to remove or change the location of a picture, for the reason that hooks heretofore made have no provision for preventing their being lifted or sprung off the molding.

25 The invention consists in a picture-hook composed preferably of sheet metal formed into the proper shape, having a hook proper upon its upper end to grasp the molding, also one upon its lower end to receive the picture-cord. The lower hook being of a separate piece from the upper, and pivoted to the latter, and being in the form of a turn-button or latch, which, when turned into its legitimate position, will extend beneath or beneath and behind the lower edge of the molding, and thereby prevent the entire hook being lifted or disengaged from said molding.

35 The drawings accompanying this specification, in Figures 1 and 2, show perspective views of a picture-hook containing my improvement, Fig. 1 showing the hook in the position for use, and Fig. 2 in the position for permitting it to be removed from the molding. Fig. 3 is a section of the hook as applied to a molding, and in its legitimate position to support a picture.

40 In these drawings, A represents the body of the hook, which in this instance is struck up or formed from a flat band of sheet metal, the upper part of the band terminating in a hook, B, for grasping the top of the molding, which

is shown at C, and I prefer that the upper part of this hook shall be concavo-convex in section, in order to impart stiffness and rigidity to it.

55 D represents a second but shorter plate of sheet metal disposed behind the lower end of the band A, and pivoted approximately near its upper end to the latter, as shown at a, the lower end of the plate D terminating in an upward and outwardly turned hook, a', which 60 serves to receive the picture-cord. The upper end or nose, b, of the plate D, when the latter is turned in line with the body of the hook, extends beneath and behind the lower edge of 65 the molding, as shown in Fig. 3 of the drawings, and in this position prevents lifting and disengagement of the hook proper from the molding, which now frequently occurs when removing or changing the position of a picture, owing, in some instances, to the spring of 70 the metal when the hook is relieved from the weight of such picture, and in others to being bodily detached from the molding by the stick employed to lift the cord from the hook.

75 When it is desired to remove a picture or to change its position upon the molding the button or plate D is turned at an angle, say, of forty-five degrees with the body of the hook, which removes the nose b of such plate from 80 behind the lower edge of the molding, and permits the hook to be removed from or changed in position upon the molding.

I have shown and described my hook as composed of flat sheet metal; but it may be of 85 wire bent into the proper shape, or it may be of cast metal.

I claim—

An improved picture-hook composed of two parts pivotally united, the upper portion provided with a hook adapted to grasp the upper edge of the molding, and the lower portion provided with a hook to receive the cord, and an upwardly-projecting nose to pass behind the lower edge of the molding, all substantially as set forth.

In testimony whereof I affix my signature in presence of two witnesses.

FRANKLIN P. BAKER.
